Primary Examiner — Jae Liang*Assistant Examiner* — Tia Ruth-Renee Polidori(57) **CLAIM**

The ornamental design for a camping grill, as shown and described.

DESCRIPTION

FIG. 1 is a perspective view of a camping grill showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions of the camping grill shown in broken line form no part of the claimed design.

1 Claim, 7 Drawing Sheets(56)
